UNITED STATES PATENT OFFICE.

FREDERICK A. STEVENS, OF PROVIDENCE, RHODE ISLAND.

DESIGN FOR AN EYEGLASS-GUARD.

44,423.

Specification for Design.

Patented July 29, 1913.

Application filed May 14, 1913. Serial No. 767,711. Term of patent 7 years.

To all whom it may concern:

Be it known that I, FREDERICK A. STEVENS, a citizen of the United States, residing at Providence, in the county of Providence and State of Rhode Island, have invented a new, original, and ornamental Design for an Eyeglass-Guard, of which the following is a specification, reference being had to the accompanying drawing, forming part thereof.

The figure represents the guard in side view.

I claim:

The ornamental design for an eyeglass guard, as shown.

FREDERICK A. STEVENS.

Witnesses:

H. B. BURKE,
J. A. SWEENEY.
